US00D994490S

(12) **United States Design Patent** (10) **Patent No.:** **US D994,490 S**
(45) **Date of Patent:** **** Aug. 8, 2023**

(54) **BOTTLE WITH CAP**

(71) Applicant: **The Procter & Gamble Company**,
Cincinnati, OH (US)

(72) Inventors: **Lifang Niu**, Singapore (SG); **Julian Richard John Gruzelier**, Founex (CH); **Li Mei Ng**, Singapore (SG); **Akiko Taneko**, Singapore (SG); **Wei Gu**, Singapore (SG); **Seiichi Ido**, Singapore (SG); **Shun Ping Pek**, Tokyo (JP); **Pamela Ruo Yan Lee**, Tokyo (JP); **Jacky Man Hin Ko**, Tokyo (JP)

(73) Assignee: **The Procter & Gamble Company**,
Cincinnati, OH (US)

(**) Term: **15 Years**

(21) Appl. No.: **29/725,021**

(22) Filed: **Feb. 21, 2020**

(30) **Foreign Application Priority Data**

Aug. 21, 2019 (CN) 201930455241.9
(51) **LOC (14) Cl.** **09-01**
(52) **U.S. Cl.** **D9/521; D9/564**
(58) **Field of Classification Search**

CLAIM

The ornamental design for a bottle with cap, as shown and described.

DESCRIPTION

FIG. 1 is a first perspective view of a bottle with cap, showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
